His Attorney.

UNITED STATES PATENT OFFICE.

DAVID BASCH, OF SCHENECTADY, NEW YORK, ASSIGNOR TO GENERAL ELECTRIC COMPANY, A CORPORATION OF NEW YORK.

CABLE TERMINAL.

Application filed January 31, 1928. Serial No. 250,903.

The present invention relates to cable terminals and connecting means whereby two or more cables may be connected together.

It is the object of my invention to provide a terminal of great strength and durability and which is an integral part of the cable body, without soldered or other high contact resistance and low strength joints.

In accordance with my invention, the ends of the desired number of sectors constituting a cable are placed in a mold along with the ends of a plurality of terminal or connector plates, and molten metal is poured into the mold so that the ends of the sectors and the terminal plates will be securely held together and bonded together metallically and structurally, the result being a strong cable terminal using a minimum of copper, and having a minimum of resistance and alternating current losses when used in a high current, high frequency line.

My invention may be better understood by reference to the accompanying drawing in which Figs. 1, 2, 3 and 4 respectively, illustrate the first four steps in the manufacture of a cable terminal, Fig. 5 represents the completed article and Fig. 6 illustrates a step in a slightly different method.

In Fig. 1 I have shown the end of a six sector cable but obviously the cable may be composed of any other number of sectors. Each of these sectors 10 is composed of a multiplicity of wires 11 twisted so that each group of wires forms a sector complete in itself. The sectors 10 are brought together and cut off so that the ends will be in a plane perpendicular to the longitudinal axis. Cylindrical sleeves 12 are tinned or otherwise coated with a suitable brazing material on the inside and the outside and are then placed over the ends of the respective sectors in a position such that the outer edges of the sleeves are flush with the extreme ends of the sectors. The end of each sector is then compressed in a hydraulic press to a triangular shape, as shown in Fig. 2 at 13. A copper insert or spacing member 14 is then placed between the ends of the sectors as shown in Figs. 3 and 4. This copper insert serves to hold the ends of the sectors in spaced relation with each other so that the molten metal may freely penetrate and surround the end of each sector.

In Fig. 2 are shown bar inserts or terminal plates 15 which are used as the connecting

medium between the adjacent ends of different cables. Each of these terminal plates consists of a narrow portion 16 and a wider portion 17. A slot 18 passes through the narrow portion 16 and almost through the wider portion 17. In the narrow portion 16 are perforations 19 and in the wider portion 17 are apertures 20. The purpose of the perforations 19, apertures 20 and the slot 18 will be brought out hereafter.

The ends of the sectors 10 are then placed in a mold as shown in Fig. 3 in a position such that the spacing member 14 will be at one edge of the mold. The terminal plates 15 are placed with the major part of the narrow portions 16 in the mold and each plate 15 is held spaced from the adjacent plate in a position substantially as shown in Fig. 2 being assembled in a core with bolts and spacing washers of proper thickness. The molten metal, preferably copper, is then poured into the mold and when this metal is cooled and is removed from the mold it will be shaped substantially as shown in Fig. 4. The slots 18 are then cut all the way through the wider portions 17 of the terminal plates, as shown at 19' in Fig. 4, and the cable may then be insulated such as by a covering of tape 21, as shown in Fig. 5. When the molten metal is poured into the mold it fills the spaces between the narrow portions of the plates 15 and also fills up the perforations 19 and that part of the slot 18 which is within the mold. The terminal plates 15 are thus very securely held by the metal 22. Since the slots 18 are not cut completely through the plates 15 that portion of the metal remaining between the ends of the slots 18 and the long edge of the plates 15 allows these plates to be held in the mold in the proper position. After the slots have been cut completely through the plates, as shown at 19', in Fig. 4, the remaining sections of the plates are rendered more flexible and better and more uniform contact pressure is obtained. When it is desired to join or splice two or more cables the plates 15 of one cable terminal are interleaved with the plates of another terminal and bolts or other securing means are passed through the apertures 20. It can be seen that two cables may be joined together end to end, or if desired, additional cables may be joined at right angles.

Instead of the use of the sleeves 12 the ends of the sectors may be compressed as

shown in Fig. 6, using a hydraulic or similar press the jaws of which are connected to the secondaries of a high current low voltage transformer. In this case before compression a low melting point brazing material which also serves as a scavenger for the copper surfaces is distributed through the wires of each sector and on compression and heating this brazing material is melted and the result is a substantially solid end portion. A spacing member 14 is then used as in Figs. 2 and 3 and the process is continued as before described.

Due to the use of the brazing material on the sleeves 12 or as distributed among the wires of the sectors as shown in Fig. 6 an alloying action takes place between this brazing material, the wires 11 and the metal 22 as described with reference to Fig. 6 or between the brazing material, wires 11, sleeves 12 and the metal 22 as described with reference to the method illustrated in Figs. 1 through 4. Similar alloying action takes place between the bar inserts which are tinned before casting, and the casting proper.

As before stated the cable may consist of any number of sectors, the process being the same as herein outlined with the exception that the spacing member 14 will be of a shape corresponding with the number of sectors used.

What I claim as new and desire to secure by Letters Patent of the United States is:

- 35 1. A cable terminal comprising a plurality of spaced metallic plates secured in conductive relation to the cable by means of a connector cast around said cable and plates.
- 40 2. A composite metal article comprising a plurality of strands of metal, said strands being divided into groups, a metallic plate and a member of cast metal surrounding and joining said groups of strands and said plate.
- 45 3. A cable connector comprising a multiplicity of copper wires divided into a plu-

rality of groups, a metallic spacer member separating said groups of wires, a plurality of copper plates and a member of cast copper surrounding and joining said wires, spacer and plates.

4. A composite metal article comprising a plurality of strands of wrought cupreous metal, said strands being divided into groups, a metallic spacer member a plurality of plates of cupreous metal and a member of cast cupreous metal joining said strands and said plates.

5. A composite metal article comprising a plurality of connector divided into groups, a metallic spacing member for holding said groups in spaced relation, a plurality of perforated plates and a member of cast metal surrounding and joining said groups of connectors, said spacing member and said perforated plates.

6. A cable connector comprising a multiplicity of copper wires divided into a plurality of groups, a copper sleeve sweated around each group of wires, a metallic member adapted to separate and space said groups, a plurality of copper plates and a member of cast copper surrounding and joining said sleeves, spacing member and plates.

7. The method of forming a terminal on the ends of a plurality of electrical conductors which consists in holding said conductors in spaced relation with each other and with a plurality of terminal connector plates, and then casting a metallic member around the ends of the conductors and the ends of the connector plates.

8. The method of uniting a multiplicity of electrical conductors with a terminal connector plate which consists in compressing the ends of each group of conductors into a substantially solid form, maintaining said groups in spaced relation with each other, and casting around said spaced ends and said terminal plate a metallic member.

In witness whereof, I have hereunto set my hand this 30th day of January, 1928.

DAVID BASCH.
